UNITED STATES PATENT OFFICE.

ABNER WESSON, OF MEMPHIS, TENNESSEE.

WIRE FENCE.

SPECIFICATION forming part of Letters Patent No. 242,725, dated June 7, 1881.

Application filed March 19, 1881. (No model.)

To all whom it may concern:

Be it known that I, Dr. ABNER WESSON, of Memphis, in the county of Shelby and State of Tennessee, have invented a new and useful Improvement in Wire Fences; and I do hereby declare that the following is a full, clear, and exact description of the same.

My invention has for its object to provide an improved fence of the class in which the posts are made of iron and the body of iron wires, that are held in slots formed in the sides of the posts.

The improvement consists in the construction and combination of parts, as hereinafter described and claimed, reference being had to accompanying drawings, in which—

Figure 1 is a side view of a lengthwise section of my fence, and Figs. 2 and 3 are vertical sections of the same on lines $x x$ and $y y$, respectively, of Fig. 1. Fig. 4 is an edge view of one of the ties, showing it prepared for application to the wires. Fig. 5 is a side view of a portion of one of the fence-posts with wire in cross-section, one slot or slit being shown open to receive a wire and protecting-wrapper of pewter, while another wire and its wrapper are shown clamped in the slot by the closed tongue b .

The letter A indicates the posts, B the wires, and C ties for connecting the wires vertically. The posts A are constructed of thin, narrow wrought-iron plates, whose lower ends, a , are pointed to adapt them to be driven like stakes, which is a matter of great importance in respect to easy, rapid, and economical erection of the fence. To enable the posts to successfully resist this lateral strain without being displaced or inclined from the vertical, points a are twisted a quarter round, so that the transverse plane of the latter is at right angles to that of the body or upper portion of the posts, as shown. The posts A are slotted diagonally at different points on one edge, thus forming a series of open slots to receive the wires B. The slits are made by a suitable machine in the process of manufacturing the posts. By thus slitting the posts a series of flexible tongues or points, b , are formed, which project upward and outward, as shown in Fig. 2. After the wires have been inserted in the slots these tongues are forked inward and the slots

thereby closed, as hereinafter more fully described.

The ties C are oblong wrought metal plates, and they are provided with a series of holes, d , corresponding in number and local relation with the wires B. From each hole d a slit extends outward to the edge of the tie. The lower ends of the ties are bent laterally, thus forming flat feet of six inches or more in length.

In erecting the fence the posts A are first driven, like stakes, by means of a maul or other suitable implement. The wires B are then firmly secured at one end of the line of fence and stretched alongside the posts, and successively raised and dropped into the slot in the posts A, and a piece of sheet lead or pewter, e , wrapped around each wire B at the points where it rests in the slots. The wires being then subjected to due tension, the points or tongues b are forced inward by giving them a light tap with a hammer, thus causing it to compress the lead or pewter e around the wires and tightly clamp the latter. The operation is quickly effected and the wires securely fastened without abrading their tinned surface, so that they are not liable to rust at the points of contact with the posts. The means of fastening are integral portions of the fence, and hence cannot be separated or become detached therefrom, which is advantageous both in transporting and setting up the fence, and also in the matter of economy, since the fastenings are made by one and the same operation of cutting the slits from the wire. To enable the tongues to hold the lead or pewter pieces more securely, I prefer to notch the edges of the slit, as shown in Fig. 2, thus forming blunt teeth that bite or indent the soft metal. Changes of temperature will occasion contraction and expansion of the wires, so that they alternately tighten and slacken throughout the length of fence. Hence in other wire fences abrasion of the tinned surface of the wires necessarily results from such movement, which cannot occur in this case owing to the interposition of the lead or pewter between the iron surfaces. The ties C are next applied, which is effected by turning outward (by means of pliers) the tongue or portion of the metal separated by the slit, Fig. 4, which opens a slot of sufficient dimensions to receive the wires B.

The ties being placed in position, the edges thus turned outward are bent back to their original position, thus closing the slot and securely attaching the ties to the wires, as shown in Figs. 5 1 and 3. The feet *f* of the ties are set in the earth to the depth of six inches or a foot. The holes in the ties are of slightly less diameter than the wires, so that the latter will be tightly clamped and the ties thus held securely in 10 place thereon. The ties *C* prevent sagging or separation of the wires and hold all of them the same distance apart, and impart strength and rigidity to the fence as a whole.

Thus constructed, the fence is cheap, strong, 15 durable, and may be erected easily and rapidly.

In some cases it is desirable to form the fence-panels of planks or boards, and to provide for such contingency I punch in each post 20 a central row of holes, *g*, Fig. 2, so that the planks or boards may be attached by means of nails driven through the holes. In such case, however, the posts are driven with their flat sides parallel to the line of the fence, in-

stead of at right angles thereto, and the ends 25 of the planks are lapped one on another, the overlapping one being nailed to the inner one and the latter to the post.

I am aware that metal fence-posts have been provided with slots to receive wires; also, that 30 pieces of tin or other semi-rigid sheet metal have been secured in such slots by means of tongues or flanges formed on said pieces themselves, so that the wires might slide on the said pieces without abrasion; but these features I disclaim as forming no part of my invention.

What I claim is—

The combination, with the metal posts having slits and tongues, as specified, and the 40 wires *B*, of the soft-metal pieces *e*, which are wrapped around the wires and secured in place by the clamping action of the aforesaid tongues, all as shown and described.

A. WESSON.
